UNITED STATES PATENT OFFICE.

MARY ANGELA COMAN, OF PHILADELPHIA, PENNSYLVANIA.

DESIGN FOR A WAITER'S CABINET.

SPECIFICATION forming part of Design No. 25,847, dated July 28, 1896.

Application filed May 27, 1896. Serial No. 593,349. Term of patent 14 years.

To all whom it may concern:

Be it known that I, MARY ANGELA COMAN, a citizen of the United States, residing at Philadelphia, in the county of Philadelphia and State of Pennsylvania, have invented certain new and useful Improvements in Designs for Waiters' Cabinets; and I do declare the following to be a full, clear, and exact description of the invention, such as will enable others skilled in the art to which it appertains to make and use the same, reference being had to the accompanying drawing, which forms a part of this specification.

The figure is an isometrical view of my design, showing it open for the reception or withdrawal of dishes of food, its essential feature being to easily convey quantities of food from the place where it is prepared to the place where it is served, and to screen it from flies, dust, &c., while awaiting use. The back, ends, top, and bottom are inclosed and compartments are formed by shelves. A ledge around the top serves as a tray or receptacle for such dishes as have been emp-

tied of their contents and are ready to be taken away for refilling or cleansing. Rollers or casters under the bottom enable the cabinet to be rolled to its destination. The shelves are perforated to enable steam or heat to arise and pass out, similar perforations being made in the back above the top shelves. The front corners are rounded and guide flexible doors, which slide within the ends or are withdrawn therefrom to close the front. The outer case may be made with panels and semicircular ends or other finish, as narrow beaded strips, according to taste or desire for ornamentation.

What I claim is—

The design for a waiter's cabinet herein shown and described.

In testimony whereof I affix my signature in presence of two witnesses.

MARY ANGELA COMAN.
